Ekleer 16" Portable Type C USB Monitor, available in Amazon.co.uk date first available Nov. 2, 2022 [online], [site visited Apr. 9, 2025], Available from the internet URL: <https://www.amazon.co.uk/EKLEER-Portable-Monitor-Charging-supplied/dp/B0BL8MGH6W> (Year: 2022).*

Primary Examiner — Catherine S Posthauer*Assistant Examiner* — Angel R Marrero-Arce(74) *Attorney, Agent, or Firm* — NSIP Law(57) **CLAIM**

The ornamental design for a portable monitor as shown and described.

DESCRIPTION

FIG. 1.1 is a perspective view of a portable monitor showing my new design;

FIG. 1.2 is a front view thereof;

FIG. 1.3 is a back view thereof;

FIG. 1.4 is a left-side view thereof;

FIG. 1.5 is a right-side view thereof;

FIG. 1.6 is a top view thereof;

FIG. 1.7 is a bottom view thereof;

FIG. 1.8 is a perspective view thereof; and

FIG. 1.9 is a perspective view thereof.

The characteristic feature of the design lies in the shape.

(Continued)

The reproductions 1.8 and 1.9 show the portable monitor in a state of use.
